UNITED STATES PATENT OFFICE.

FRÉDÉRIC GRUNIG, OF BROOKLYN, AND MAXIME L. VAN HUELE, OF NEW YORK, N. Y.

ADJUSTABLE HAT-LINING.

1,396,421.

Specification of Letters Patent.

Patented Nov. 8, 1921.

Application filed August 4, 1919. Serial No. 315,295.

To all whom it may concern:

Be it known that we, FRÉDÉRIC GRUNIG, a citizen of Switzerland, and a resident of the city of New York, borough of Brooklyn, in 5 the county of Kings and State of New York, and MAXIME L. VAN HUELE, a subject of the King of Belgium, and a resident of the city of New York, Corona, borough of Queens, in the county of Queens and State 10 of New York, have invented a new and Improved Adjustable Hat-Lining, of which the following is a full, clear, and exact description.

The invention relates to bandaux, hat linings and similar articles provided with hoops having overlapping ends to permit of adjusting the lining to hats of different sizes and such, for instance, as shown and described in the Letters Patent of the United 20 States, No. 1,225,618, granted to us on May 8, 1917.

The object of the present invention is to provide a new and improved adjustable lining for women's hats arranged to permit, 25 first, to fit the lining to any sized hat, and then fit the hat by means of the lining to any sized head. Another object is to dispense with the hoop and with the objectionable puckering or gathering of the material occasioned by the constriction of the outer 30 edge of the lining from full size to a smaller size. Another object is to provide a lining not liable to leave any marks on the user's forehead even should the hat fit closely or 35 tightly on the head. Another object is to give a smooth, neat finish to the hat.

With these and other objects in view, the invention consists of certain novel features of construction as hereinafter shown and 40 described and then specifically pointed out in the claim.

A practical embodiment of the invention is represented in the accompanying drawings forming a part of this specification, in 45 which similar characters of reference indicate corresponding parts in all the views.

Figure 1 is a perspective view of the blank for forming the side portion of the crown of the hat lining;

50 Fig. 2 is a plan view of the side portion of the crown partly sewed to the flat top;

Fig. 3 is an inverted plan view of the adjustable hat lining;

55 Fig. 4 is a similar view of the same prior to adjusting it;

Fig. 5 is a similar view of the same show-

ing one end of the constricting cord or string drawn out of a cut in the hem for adjusting the lining to hats smaller than the full-sized lining; and

Fig. 6 is a sectional side elevation of the adjustable hat lining in position in the hat.

The crown of the adjustable hat lining comprises a side portion 10 made of silk, satinet or a similar flexible fabric, and a top 11 made of a similar material but usually stiffened and of oval shape to conform to the shape of the crown of the hat in which the lining is used. The side portion 10 is cut at a bias, as plainly shown in Figs. 1 and 2, and a hem 12 is formed lengthwise of the side portion intermediate the sides thereof to provide an attaching portion 13 doubled up in an outward direction and fastened at the bend 14 by stitches 15 to the hat 16, as plainly indicated in Fig. 6. In the hem 12 is arranged a constricting member 20, preferably in the form of a draw string of an elastic or non-elastic material with the ends projecting beyond the hem 12.

In attaching the upper edge of the side portion 10 to the margin of the oval or elliptical top 11, the operator sews on one upper corner of the side portion 10 to the margin of the top 11 to one side of the major axis of the top 11 at a point 30 indicated in Fig. 2, and the operator in sewing the upper edge of the side portion 10 to the margin of the top 11 gathers the said upper edge, and on finishing the operation the other upper corner terminates or slightly overlaps at the beginning point 30. Now owing to the bias cut of the side portion 10, the adjacent sides of the side portion 10 extend diagonally downwardly and rearwardly approximately to the back of the lining, as will be readily understood by reference to Fig. 3. It will be noticed that the sides of the side portion 10 are in close proximity to each other and can be drawn into more or less overlapping relation by hand, and then the ends of the constricting member 20 are tied preferably into a bow 21. The bow is located at the back of the hat. It will be noticed that the hem 12 and the constricting means 20

105 permit of adjusting the lining to fit snugly on the head of the wearer. In case considerable reduction has to be made in order to 110 properly fit the lining to the hat, it is only necessary for the user to cut the hem 12

at a point 22 located the necessary distance inward from one end of the hem, as plainly shown in Fig. 5, to permit the user to draw out this end 20 through the cut portion at 5 the point 22, and place the end of the side portion in which the hem has been cut under or behind the other end of the side portion in overlapping relation so that both protruding ends of the constricting member emerge 10 from the hem in adjacent relation. The two ends of the constricting member 20 are now to be tied into a bow 21 and it is evident that the circumference of the lining has been decreased to insure a proper fit of the 15 lining in the hat. By adjusting the elastic 20 in the hem to give it more or less tension, the lining is properly fitted to the wearer's head. Thus by the arrangement described the lining can be correctly fitted into any size 20 hat and the hat can then be adjusted to fit the wearer's head.

It will be noticed that by doubling up the edge of the attaching portion 13 in an outward direction and fastening the bandeau 25 14 to the hat an exceedingly fine finish is given to the lining, and by arranging the bow 21 at the back it is not liable to interfere with the comfort of the wearer as the bow is at the wearer's hair. It will further

be noticed that no undesirable obstruction 30 is arranged at the front or one that is liable to leave any marks on the wearer's forehead.

Having thus described our invention, we claim as new and desire to secure by Letters Patent:—

As an article of manufacture, a hat lining comprising a crown having a gathered top and a side portion formed of a flexible material cut at a bias, the sides of the said side portion being in overlapping relation, 40 the lower edge of the said side portion being doubled up outwardly to form an attaching edge for fastening the lining into the hat, the lower portion of the said side portion being provided with an integral hem a 45 distance from the said attaching edge and intermediate the latter and the top, and a draw string in the said hem, one end of the said draw string projecting beyond the corresponding end of the hem, the latter 50 having an opening a distance from its other end for the passage of the other end of the draw string to allow of fastening the ends of the draw string together with the hem ends in overlapping relation.

FRÉDÉRIC GRUNIG.
MAXIME L. VAN HUELE.
